INKWELL

Earl R. Groo and Jack I. Green, Brooklyn, N. Y.

Application September 21, 1938, Serial No. 230,920

3 Claims. (Cl. 120—57)

This invention relates to inkwells and has for one of its objects the provision of an inkwell which is so constructed that only pen points of a predetermined size and shape may be inserted into the ink compartment.

More specifically, the object is to provide an inkwell which is so constructed and organized that fountain pens cannot be filled from ink in the well. It is a matter of common knowledge that banks, post offices, hotel writing rooms and the like are put to considerable expense over a period of time, and later intending users are greatly inconvenienced, by the practice of filling fountain pens from inkwells which are provided on writing desks and to which the public has access. The consumption of ink is multiplied many times as compared with what it should be and clients and patrons for whom the service is supplied are apt to find the ink exhausted and have to wait until the well is again filled or find another well which has some ink left.

The construction of the improved inkwell also has the advantage that evaporation is reduced to a minimum, due to the fact that the ink is not exposed to the atmosphere in the usual sense, the only opening being one of such small extent that evaporation through said opening is negligible.

Still another object is to provide an inkwell for the purpose stated which will have a cover which cannot readily be removed by anyone who has not been informed as to how to do it and who is not provided with an implement suitable for the purpose. The construction in this respect is such that proper relation and alignment of parts constituting a pen receiving opening, is maintained at all times. This will become clearer later on.

Another and incidental object is to provide a construction which is simple and which can be manufactured at a low cost, but which will nevertheless serve the stated purposes in an efficient manner.

With the foregoing and incidental objects in view, the invention consists in a novel construction and relation of parts, illustrative embodiments of which are shown in the accompanying drawing and explained in the following, and the novel features of which are pointed out in the claims appended hereto.

In said drawing:

Fig. 1 is a top plan view of an inkwell to which one form of the invention has been applied.

Fig. 2 is a section along the line 2—2 of Fig.

1, and shows how a selected type of pen point may be inserted.

Fig. 3 shows in perspective the inkwell cover employed in Figs. 1 and 2 and shows how the structure for allowing the insertion of certain pen points, while preventing the insertion of others, may be supported from the top or cover of the inkwell.

Fig. 4 shows a modification of the inkwell of Figs. 1, 2 and 3, and is in some respects the form 10 preferred.

Fig. 5 is a view from the bottom of the inkwell of Fig. 4 and shows how the cover or top is held in place.

Fig. 6 is a fragmentary side view of the inkwell and shows details of the construction for latching the cover in place on the ink receptacle.

The form of construction illustrated in Figs. 1, 2 and 3 has a container 9 for ink which may be of any suitable size or shape and of any suitable material. The upper part of the container is threaded on the exterior to cooperate with corresponding threads formed in the skirt 10 of a top or cover 11. The top is provided with a circular hole 12 which is preferably located at the center of the cover 11, although neither the shape of the hole nor its location are essential things. It may be non-circular or it may be located at any desired point in the cover top.

Centered in the hole 12 is a part which is, for want of a better name, referred to herein as the post 13, which is cylindrical in the form shown, with an annular ring or clearance 14 between the edge of the hole and the periphery of the post which is preferably the same in width at all points. Here again the exact location of the post with reference to the hole is not a matter of exactness, although in a circular well such as shown it is desirable that a pen point can be inserted with equal facility at any place between the edge of the hole and the periphery of the post. The important thing is to so proportion the relations of the hole with the periphery of the post that only a pen point of a certain size and shape, such as are supplied at the particular writing desk, can be inserted in the clearance 14 far enough to take ink; and particularly to have the clearance between the post and the edge of the hole related so that the post will serve as a stop for the ink feed bar or the like of a fountain pen and thereby prevent insertion of a fountain pen far enough to permit filling the pen.

In the construction illustrated in Figs. 1, 2 and 3 the post 13 is supported by wires or the like 55

40

45

50

55

15 which are attached to the under side of the cover and to the post 13 as shown in Figs. 2 and 3 so as to support the post in position with reference to the hole in the cover. To fill the ink-well the top simply is unscrewed and removed, carrying with it the post 13 and its support 15, so that the proper relation of the post with reference to the hole 12 in the cover is at all times maintained.

10 In the form shown in Fig. 4, the inkwell 28 has formed on its bottom a post 21 projecting upward and cooperating with a hole 22 in a cover 23. Here again it is preferred that the post be centered with some exactness in the hole so 15 as to provide a clearance of uniform dimensions between the periphery of the post and the edge of the hole.

The cover 23 is removable, but it is preferred to have it held in place by a construction which will 20 permit ready removal by an attendant who knows how to do it, but which will serve as a deterrent to others who are not informed and who might want to remove the cover. For this purpose the cover 23 is made of thicker material 25 than is shown in Figs. 1 and 2 and the well is provided with a flange 24 on the upper exterior. Extending inward from a skirt or flange 25 of the cover 23 is a stud 26 preferably carrying a small soft rubber roller 27. Diametrically opposite the pin and roller is a leaf spring 28 fixed in a notch or groove in the skirt of the cover. The flange 24 is recessed or cut out at two diametrically opposite points as shown at 29, 29. After the well is filled the cover is put on with 30 the roller 27 and spring 28 passing through the recess 29 and the cover is then given a turn to engage the roller and spring under the flange 24 to hold the cover closely in position on the ink-well. On the under side of the flange 24 are 35 latching lugs 31 adjacent one or both of the recesses 29. These are shaped as shown in Fig. 6 so that after the cover is put in place with the spring 28 below the flange 24 the cover may be rotated until the spring snaps behind the vertical shoulder of one of the lugs 31. The vertical shoulders of the latching lugs 31 are not very high, so that if the lugs are used adjacent each of the recesses 29 the roller 27 will ride over them in putting the cover off and on, but the 40 shoulders are nevertheless high enough to be engaged by the edge of the spring 28 securely enough to give the desired latching effect.

The spring is formed with a loop as shown in Fig. 4, which can be engaged by a suitable implement in the possession of the attendant to flex the spring sufficiently to clear the lug 31, after which the cover may be turned until the spring reaches the recess 29, whereupon the cover can be removed for filling the well.

60 The spring latch 28 may be of any suitable shape and be attached in any suitable manner provided that some special tool or unobvious manipulation is required to remove the cover.

The arrangement of latching lugs 31 may, as 65 above suggested, be duplicated adjacent either or both of the clearances 29. If only one pair of lugs are used, in order to prevent turning the cover until the spring 28 reaches the other clearances 29, a pair of stop shoulders 32 may be pro-

vided for limiting rotation of the cover after the spring 28 has passed over one of the latching lugs 31. Or, instead of using the shoulders 32, the spring and one of the clearances 29 may be wider than the stud 27 and the other clearance, 5 so that the spring will have to be in line with the wider clearance before the cover 23 can be removed or replaced.

While the forms of embodiment illustrated in the drawing and above explained are admirably adapted to fulfill the objects and purposes stated, the invention is capable of various modifications and changes all coming within the scope of the claims which follow.

What is claimed is:

15 1. An inkwell having a post of a predetermined diameter extending upward from the inner bottom and having a flat top, and a removable cover for the well having a pen receiving opening in its top of a diameter sufficiently larger 20 than the diameter of the post to provide an annular clearance of a predetermined size between the edge of the opening and the periphery of the post, and means comprising a spring latch for removably holding the cover on the well. 25

2. An inkwell having an outwardly extending flange around the top of the ink container, said flange being cut away at two points to provide clearances, a cover for the container carrying a rubber roller and a spring spaced apart the same 30 distance as the two clearances in the flange and passing through said clearances when the cover is applied and engaging under said flange when the cover is rotated, and locking lugs on said flange adjacent the clearances cooperating with 35 the spring to limit rotation of the cover in one direction unless the spring is manipulated to clear the locking lugs in removing the cover.

3. An inkwell comprising an ink container having an outwardly extending flange around its 40 top, said flange being cut away at two points to provide spaced apart clearances or notches, a cover for the container having a central opening in its top and a downwardly extending flange, the interior of which flange will closely engage 45 the periphery of the flange on the container when the cover is in place, a cylindrical member extending up into the opening in the cover and of sufficient diameter to provide an open annulus between the member and the edge of the afore- 50 said opening, a stud and a spring on the flange of the cover both extending inward and spaced apart the same distance as the aforesaid clearances or notches, said spring and stud passing through said clearances when the cover is applied and under the flange on the container when the cover is then rotated, lugs on the under 55 side of the flange on the container constructed to form cam faces which flex the spring as the cover is rotated in one direction and stop shoulders limiting reverse rotation of the cover, and other stops on the under side of the flange on the container limiting the rotation of the cover to a distance less than the spacing between the aforesaid clearances or notches, said opening being manually operable to clear said lugs and stops when the cover is to be removed.
